UNITED STATES PATENT OFFICE.

MAX BARTHOLDY, OF ESSEN-ON-THE-RUHR, GERMANY, ASSIGNOR TO FRIED. KRUPP AKTIENGESELLSCHAFT, OF ESSEN-ON-THE-RUHR, GERMANY.

LOADING DEVICE FOR TURRET OR STATIONARY GUNS.

1,090,093.

Specification of Letters Patent. Patented Mar. 10, 1914.

Application filed June 19, 1911. Serial No. 633,927.

To all whom it may concern:

Be it known that I, MAX BARTHOLDY, a subject of the Emperor of Germany, and a resident of Essen-on-the-Ruhr, Germany, 5 have invented certain new and useful Improvements in Loading Devices for Turret or Stationary Guns, of which the following is a specification.

The present invention relates to loading 10 devices for turret or stationary guns provided with a hoist for transferring the ammunition into the loading line of the gun.

The object of the invention is to provide 15 a loading device of this kind of very simple and easily accessible construction.

An embodiment of the invention is represented in the drawings, wherein:—

Figure 1 is a side elevation, partly in section, of the loading device as adapted to a 20 gun turret with recoil-mount, together with parts of turret and mount, the gun being shown in highest elevation and the ammunition car in its lowest position; Fig. 2 is a part plan view of Fig. 1, but with the 25 gun level; Fig. 3 is a part plan section on lines 3—3 of Fig. 1; Fig. 4 a vertical section on line 4—4 of Fig. 1, looking to the rear, but with details in the position they would have with the gun level; Fig. 5 is a similar side view to Fig. 1 but showing the ammunition car in loading position; Fig. 30 5^a, a diagrammatical representation of rope and pulleys; Fig. 6 a similar side view to Fig. 5, but with the gun in lowest depression; Fig. 7 shows the ammunition car and the part of its track in an end view corresponding to Fig. 4, but the details being represented in a position they would have when the gun is in highest elevation; Fig. 8 a right hand elevation of Fig. 7 partly in section; Fig. 9 a left hand section on line 9—9 of Fig. 7; Fig. 10 a section on line 10—10 of Fig. 7 seen from above; Fig. 45 11 a side view of the ammunition car, partly in section, with the details in the same position as in Fig. 6. Fig. 12 shows a detail of different construction.

50 A description of the invention embodied in Figs. 1 to 11 will now be given.

The upper platform a^1 of the mount A (Figs. 1, 5 and 6) supports the armor plate dome A^2 of the turret and the two cheeks

A³, wherein the gun cradle B with the gun 55 barrel C rests with its horizontal trunnions b^1 in the trunnion bearings. The mount rests with a ball race on top of the structural cylinder O, as shown in the drawing, and can be turned thereon around its vertical 60 axis, by means of a training gear. Said gear and the elevating gear may be of any well known kind of construction; neither are therefore shown in the drawing. The piston rods for the recoil and counter recoil buffers 65 are in Fig. 1 designated as b^2 and b^3 .

A fork D (Figs. 1, 2, 4, 5 and 6) is rigidly attached to the cradle B. A cross-piece d^1 of said fork lying behind the breech end of the gun barrel carries a chain rammer, the 70 housing of which has been called E, and the rammer head e^1 . The rammer housing E reaches forward over the gun and grips a vertical pivot b^4 of the cradle B, by means of a bearing e^2 , in such a manner 75 that said housing E may be swung side-wise out of the vertical plane of the gun's loading line. With the same object in view the rammer housing E is further provided with a jaw e^3 , gripping a table 80 edge d^2 of the cross-piece d^1 , said edge d^2 being curved concentric with the pivot b^4 .

Each of the two parallel arms of the fork D are supplied with a journal d^3 near the cross-piece d^1 . Pivoted on each journal d^3 , 85 is a T-shaped rail F (see also Fig. 10), guided in a T-shaped groove of another rail F^1 , partly inclosing said rail F. These latter rails F^1 are in their turn, hung on journals f^2 in bearings on a trestle G, which 90 rests on the loading platform a^4 . The rails F and F^1 serve as track for the ammunition car H, carrying a loading tray K.

The ammunition car H (see Figs. 7 to 11) is constructed of steel plates, riveted together and provided with eight track wheels J running on the two rail pairs F F^1 . The tires of said wheels have projecting guide flanges i^1 in the middle, which engage with the rails F^1 to provide a sure guiding of 100 the ammunition car H. This is best illustrated in Fig. 10. The ammunition car has two bearing blocks h^1 on which the loading tray K is mounted to swing on its journal k^1 . The loading tray is adapted to hold the 105 whole of ammunition of a shot (shell for cartridge and main cartridge) simultaneously.

To bring the ammunition up from the magazine, situated below the loading platform a^4 , up to a loading table T^1 on said platform, a hoist is utilized of which T is the trunk. From said hoist, the ammunition can slide over the inclined loading table T^1 onto the loading tray K ; when the ammunition car H stands in its lowest position, with the loading tray at one end resting with its bottom on the recess t^2 , of the loading table T^1 , and at the other end with its stop plate k^3 on a ledge g^1 of the trestle G . With the loading tray in this position, the axis of its journal k^1 fall in line with the axis of the rail journals f^2 .

At its forward end the loading tray K carries two arms k^4 reaching downward, having at their free end each a cylindrical projection k^5 . Said projections k^5 are intended to coöperate with ledges d^4 on the fork D , when the ammunition car H has been transferred to the loading position (Figs. 5 and 6). The cross-piece d^1 of the fork D has a recess in the middle of its under side (see Fig. 4) the walls d^5 of said recess constituting a stop for the stop k^3 of the loading tray K . With the projections k^5 , against the ledges d^4 , and the stop k^3 against the walls d^5 of the recess (Figs. 5 and 6) the axis of the tray journals k^1 coincides with the axis of the journals d^3 .

At the innerside of the forward wall of the ammunition car are situated two guides h^2 , each having a groove h^3 parallel with the rails F , F^1 . The reduced ends of journals m^1 situated on a carrier M engage said grooves h^3 . At right angles to the axis of said journals, and on the same carrier M , is pivoted a rope pulley N . To each of the journals m^1 is attached one end of a link L , the other end being pivoted on an eye k^2 on the bottom wall of the loading tray K . The rear wall of the ammunition car has a supporting surface h^4 on which the bottom wall of the loading tray is resting, while the journals m^1 stop against the upper end of the grooves h^3 .

Near the two side walls of the ammunition car H and at its upper end, two rope pulleys N^1 are journaled in such a manner, that their grooves lie in the same plane as the groove of the pulley N . A transmission rope P is swung around the pulleys N , N^1 and conducted to the rope drum P^1 (see Figs. 1, 3, 5 and 6) of a hoisting device situated on the hoist trunk T , by a set of pulleys Q to Q^8 arranged in pairs (see Figs. 2, 3 and 4). In using the term rope in the specification and claims I mean to include an equivalent flexible connection.

The conducting of the rope P to the drum P^1 is accomplished in the following manner: The rope is placed on the under side of the pulley N and on the outside of the pulleys N^1 . From said pulleys N^1 onward, both

rope halves run parallel with the rails F , F^1 , until turned over the two pulleys Q , in the immediate neighborhood of the journals d^3 on the fork D . The rope is, from there on, carried by means of two pairs of pulleys, one pair Q^1 of which is journaled on the fork D , and the other Q^2 directly on the cradle B , to two pulleys Q^3 journaled on the trunnions b^1 . The two pairs of pulleys Q^1 and Q^2 have been provided, in order to prevent the rope interfering with the accessibility of the breech closure. From pulleys Q^3 the rope is taken over a pair of pulleys Q^4 , journaled at the forward end of the cradle B , in approximately vertical direction to two pulleys Q^5 . Said pulleys Q^5 , as well as two other pairs of pulleys Q^6 and Q^8 are carried on two bearing brackets a^6 , situated on the under side of the middle platform a^5 of the mount A . From pulleys Q^5 , the rope P is lastly carried over pulleys Q^6 , under pulleys Q^7 , and over pulleys Q^8 to the drums P^1 of the hoisting device. The two drums P^1 are mounted on a common shaft p^2 , which is coupled to the motor, not shown.

Between the bearing brackets a^6 underneath the platform a^5 , the piston rod r^1 , of a hydraulic buffer is attached; the cylinder of said buffer being called R , and the piston r^2 . For transferring the hydraulic fluid from one side of the piston to the other, canals r^3 are provided in the piston r^2 . From end to end a groove r^4 is cut on the inside of the cylinder R , engaging a key (not shown) on the piston. This arrangement has been made in order to prevent any turning of the cylinder. On the cylinder head r^5 are situated two rope pulleys Q^7 , which lie in the same planes as the other pulleys Q , Q^1 , Q^2 , etc. The cylinder R is thus suspended on the rope P , by means of the pulleys Q^7 . The weight of said cylinder is chosen so as to keep the rope taut, at all mutual positions of the parts, without raising the ammunition car H with the loading tray K .

With the gun C in highest elevation and the ammunition car H in its lowest position, the different parts will take the relative position indicated in Figs. 1 and 7 to 10. The loading tray K is there shown resting with its bottom both on the recess t^2 of the loading table T^1 and on the supporting surface h^4 of the ammunition car H ; as well as with its stop plate k^3 on the ledge g^1 of the trestle G . The axis of the journals f^2 , situated on the rails F^1 , coincides with the axis of the loading tray journals k^1 . The journals m^1 of the carrier M for the pulleys N are resting against the upper end faces of the guide grooves h^3 provided in the guide pieces h^2 ; and the rails F are entirely inclosed by the rails F^1 . The cylinder R is in its lowest position relative to the piston r^2 and keeps the

rope taut. If now, by means of the elevating gear, the elevation of the gun is changed, the rails F, journaled to the fork D, will be displaced, upward, relative to the rails F¹. The rails F, F¹, together with the ammunition car H, simultaneously execute a slight rocking movement about the axis of the journals f²; the loading tray K, on the other hand, retains its position relative to the loading table T¹, and to the ledge g¹ of the trestle G, on account of the axis of the tray journals h¹, at the lowest position of the ammunition car, coinciding with the axis of the journals f². As a consequence, ammunition from the trunk T may be loaded on the tray K, while the gun is being elevated. As, however, the ammunition car H oscillates around the axis of the journals f², as described above, when the elevation of the gun is changed, a slight movement of the journals m¹ in the guide grooves h³ will take place. Simultaneously, the supporting surface h⁴ of the ammunition car will move away slightly from the bottom of the loading tray. If also, the gun barrel be elevated slightly out of the position indicated in Fig. 1 or finally moved to its full depression, as shown in Fig. 6, the brake cylinder R will be raised by means of the rope P and the pulleys Q¹, as thereby the distance between pulleys Q and the pulley N of the ammunition car, which is being kept at its lowest position by its weight, is increased with the gun in lowest depression, the rails F, F¹ and the cylinder R will take the relative positions shown in Fig. 6. If the elevation of the gun is altered from its depressed position, the cylinder R will again run down. In pointing the gun, the rope P will, therefore, constantly be held taut by the cylinder R.

When it is desired to transfer the ammunition, placed on the loading tray K, into the loading line of the gun, the hoisting gear P¹, p² is set in motion. Supposing now that the gun lies in an elevation that does not require the cylinder R to be in its highest position; in starting the hoisting gear, the cylinder R will then be raised to its highest position, whereupon the ammunition car will be carried upward on the rails F, F¹. The passing of the cylinder fluid from one side of the piston r² to the other, through the canals r³, will add a load on the rope P, considerably greater than the one caused by the weight of the brake cylinder alone. As a consequence the resistance to movement, which obtains from raising the loaded ammunition car, following the raising of the cylinder R, does not suddenly increase the strain on the rope to such an extent that the rope will break. If the gun lies in lowest depression before the starting of the hoisting gear, the cylinder R then assumes its highest position, but any danger of breaking the rope in raising the ammunition car will still

be eliminated, as the hoist motor is started slowly, and the rope consequently receives a gradual increase of its load.

In raising the ammunition car H, the car and the loading tray K will be in the relative positions shown principally in Figs. 7 to 9. The rope P, by means of the pulleys N, the carrier M, and the links L, is then holding the loading tray in such a position, that the journals m¹ rest against the upper end of the guide groove h³, and that the loading tray rests with its bottom on the supporting surface h⁴ of the ammunition car. Toward the end of the travel upward of the ammunition car, the projections h⁵ on the tray arms h⁴ will strike against the ledges d⁴ of the fork D. In consequence, the loading tray will be forced to swing around its journals h¹ until the projectile lying in the middle portion of the tray lies in the loading line, in case the tray should happen to have a different inclination, relative to the ammunition car than the gun. With the loading tray in this position, the stop plate h³ thereof will rest against the recess walls d⁵ of the fork cross-piece d¹. The ammunition may then be rammed into the gun by means of the rammer E, e¹, driven by a motor; or by hand after the rammer has been swung to the side around its pivot e², b⁴. When the ammunition car has taken up the position illustrated in Figs. 5 and 6, the axis of the tray journals h¹ will, as mentioned above, coincide with the axis of the journals d³ that connect the rails F with the fork D. These circumstances together with the action of the pairs of pulleys Q³, Q⁴ on the position of the rope P which will be explained further on will cause the loading tray to remain in the loading line of the gun, while the elevation of the gun is being changed and that the ammunition consequently may be rammed even when the gun is being elevated or depressed. The following will explain the action of the pulleys Q³, Q⁴ on the position of the rope:—When the ammunition car is in the loading position and the elevation of the gun is being changed, the angular position of the loading tray relative to the ammunition car will also change, as will be understood from Figs. 5 and 6, in consequence of the coöperation between the projections h⁵ and the ledges d⁴ on the one hand; and the stop plate h³ and the recess walls d⁵ on the other hand, in such a direction that the journals m¹ will be pushed downward in the guide grooves h³ by the links L when the breech end of the gun is raised. As the pulley N always must follow the movement of the journals m¹, the distance between said pulley N and the pulleys Q will be increased, requiring slight addition to the rope length which must be taken care of. This will be done by the roller pairs Q³ and Q⁴, as, while raising the breech end of the gun, the rope

P, on the one hand, will partly unwind from the pulleys Q³, and on the other hand, the angle the rope makes between the pulleys Q³ and Q⁵ will become larger on account 5 of the position given to the pulleys Q⁴. A comparison of the conditions in different positions of the rope P and the pulleys Q², Q⁴ is illustrated in Fig. 5^a, wherein the full lines indicate the position with the gun in 10 highest elevation, and the dotted lines indicate the position with the gun in deepest depression. Should the breech end of the gun be lowered, the journals m¹ will, on the contrary, move upward in the guide grooves 15 h³. If provision was not then made for taking up the slack of the rope by means of the described arrangement of the pulleys Q³ and Q⁴, the ammunition car would move downward, and the position of the loading 20 tray K as regards the gun would change. That this does not take place will again be seen from Fig. 5^a.

After the ramming of the ammunition into the gun, the motor of the hoisting gear 25 P¹, p² will be started to lower the ammunition car. If the gun is not to have the lowest depression imparted to it, the ammunition car will be lowered first, and then the cylinder R. The letting down of the 30 ammunition car may therefore take place directly after the loading, since the rammer is situated above the hoist, and before the rammer has been retracted from the gun chamber. No explanation of the working in 35 other respects of the above described arrangement, will be necessary.

With the arrangement as indicated in Fig. 12, the pulleys Q⁷ are attached to a hollow member S, which is carried on a rod s¹ secured under the platform a⁵. A strong spring U is inserted between the hollow member S and a head s² on the rod s¹. This arrangement operates practically in the same manner as the above described fluid 45 brake R, r¹, r².

Without changing the substance of the invention, the rope P might be run in a single line from the ammunition car H to the hoisting gear P¹, p². The pulleys Q, Q¹ to Q⁸ 50 would then be used singly and not in pairs.

Having thus described my invention, what I claim as new, and desire to secure by Letters Patent, is:—

1. A loading device for turret or stationary guns, provided with an ammunition car hoist, for placing the ammunition in the loading line of the gun, a track for said car, said track being constructed of telescopic rails and journaled respectively on a gun 55 part that partakes of the elevation and on a part of the mount that partakes of the training.

2. A loading device for turret or stationary guns, provided with an ammunition car 60 hoist, for placing the ammunition in the

loading line of the gun, telescopic rails constructed to form a track for said car, and journaled respectively on a gun part that partakes of the elevation, and on a part of the mount that partakes of the training, the 70 axes of the journals running parallel with the axis of the gun trunnions.

3. A loading device for turret or stationary guns, provided with an ammunition car hoist, for placing the ammunition in the loading line of the gun, telescopic rails constructed to form a track for the ammunition car, and journaled respectively on a gun part that partakes of the elevation and on a part of the mount that partakes of the training, a loading tray journaled to oscillate on the ammunition car, the axis of the 75 journals of said tray running parallel with the axis of the gun trunnions.

4. A loading device for turret or stationary guns, provided with an ammunition car hoist, for placing the ammunition in the loading line of the gun, telescopic rails constructed to form a track for said car, and journaled respectively on a gun part that 80 partakes of the elevation, and on a part of the mount that partakes of the training, the axes of the joitrnals running parallel with the axis of the gun trunnions, a loading device provided with an ammunition car hoist 85 for placing the ammunition in the loading line of the gun, a loading tray journaled on the ammunition car, the axis of the journals of said tray running parallel with the axis 90 of the gun trunnions.

5. A loading device for turret or stationary guns, provided with an ammunition car hoist, for placing the ammunition in the loading line of the gun, telescopic rails constructed to form a track for said car, and 95 journaled respectively on a gun part that partakes of the elevation, and on a part of the mount that partakes of the training, the axes of the journals running parallel with the axis of the gun trunnions, a loading device provided with an ammunition car hoist, for placing the ammunition in the loading line of the gun, a loading tray journaled on the ammunition car, the axis of the journals of said tray running parallel with the axis 100 of the gun trunnions.

6. A loading device for turret or stationary guns, provided with an ammunition car hoist, for placing the ammunition in the loading line of the gun, telescopic rails constructed to form a track for said car, and journaled respectively on a gun part that 115 partakes of the elevation, and on a part of the mount that partakes of the training, the axes of the journals running parallel with the axis of oscillation of the journals connecting said rails with the mount.

120

7. A loading device for turret or stationary guns, provided with an ammunition car hoist, for placing the ammunition in the loading line of the gun, telescopic rails constructed to form a track for said car, and journaled respectively on a gun part that 125 partakes of the elevation, and on a part of the mount that partakes of the training, the axes of the journals running parallel with the axis of the gun trunnions, a loading de- 130

- vice provided with an ammunition car hoist, for placing the ammunition in the loading line of the gun, a loading tray journaled on the ammunition car, the axis of the journals of said tray running parallel with the axis of the gun trunnions, said loading tray, when situated in the loading line of the gun, having its axis of oscillation coinciding with the axis of oscillation of the journals connecting said rails with said gun part. 70
7. A loading device for turret or stationary guns, provided with an ammunition car hoist, for placing the ammunition in the loading line of the gun, a track for said car formed by telescopic rails journaled respectively on a gun part that partakes of the elevation and on a part of the mount that partakes of the training, a loading tray journaled to oscillate on the ammunition car, the axis of the journals of said tray running parallel with the axis of the gun trunnions, and means carried respectively by said tray and by a gun part partaking of the elevation of the gun, coöperating to accurately determine the loading position of said loading tray. 75
8. A loading device for turret or stationary guns, provided with an ammunition car hoist, for placing the ammunition in the loading line of the gun, a track for said car formed by telescopic rails journaled respectively on a gun part that partakes of the elevation and on a part of the mount that partakes of the training, a loading tray journaled to oscillate on the ammunition car, the axis of the journals of said tray running parallel with the axis of the gun trunnions, said tray being provided with striking surfaces coöperating with striking surfaces on a gun part that partakes of the elevation of the gun, for the purpose of accurately determining the loading position of said loading tray. 80
9. A loading device for turret or stationary guns, provided with an ammunition car hoist, for placing the ammunition in the loading line of the gun, a loading tray journaled on the ammunition car, the axis of the journals of said tray running parallel with the axis of the gun trunnions, a hoisting rope for the ammunition car, and a member connecting the rope with the ammunition car and mounted to slide on the ammunition car, and having a connection with said loading tray through which it is made to partake of the movement of the tray relative to the ammunition car, pulleys for the rope journaled coaxially with the gun trunnions and guiding means for the hoisting rope, moved with the elevating movement of the gun and located to tighten or slacken the hoisting rope as the angle of elevation is changed, an amount corresponding to that which the rope is slackened or tightened between said connecting member and the pulleys journaled on the trunnion axis. 85
10. A loading device for turret or stationary guns, provided with an ammunition car hoist, for placing the ammunition in the loading line of the gun, telescopic rails constructed to form a track for said car, and journaled respectively on a gun part that partakes of the elevation, and on a part of the mount that partakes of the training, the axes of the journals running parallel with the axis of the gun trunnions; a rope tightening member, said member carrying means for guiding the hoist rope and maintaining the hoist rope taut, while the elevation of the gun is being changed. 90
11. A loading device for turret or stationary guns, provided with an ammunition car hoist, for placing the ammunition in the loading line of the gun, telescopic rails constructed to form a track for said car, and journaled respectively on a gun part that partakes of the elevation, and on a part of the mount that partakes of the training, the axes of the journals running parallel with the axis of the gun trunnions, a hoisting rope for the ammunition car, a pulley on each side of the gun for said hoisting rope, journaled co-axially with the gun trunnions. 95
12. A loading device, for turret or stationary guns, provided with an ammunition car hoist, for placing the ammunition in the loading line of the gun, a loading tray journaled on the ammunition car, the axis of the journals of said tray running parallel with the axis of the gun trunnions, a hoisting rope for the ammunition car, and a member connecting the rope with the ammunition car and mounted to slide on the ammunition car, and having a connection with said loading tray through which it is made to partake of the movement of the tray relative to the ammunition car, pulleys for the rope journaled coaxially with the gun trunnions and guiding means for the hoisting rope, moved with the elevating movement of the gun and located to tighten or slacken the hoisting rope as the angle of elevation is changed, an amount corresponding to that which the rope is slackened or tightened between said connecting member and the pulleys journaled on the trunnion axis. 100
13. A loading device for turret or stationary guns, provided with an ammunition car hoist, for placing the ammunition in the loading line of the gun, telescopic rails constructed to form a track for said car, and journaled respectively on a gun part that partakes of the elevation, and on a part of the mount that partakes of the training, the axes of the journals running parallel with the axis of the gun trunnions; a rope tightening member, said member carrying means for guiding the hoist rope and maintaining the hoist rope taut, while the elevation of the gun is being changed. 105
14. A loading device for turret or stationary guns, provided with an ammunition car hoist, for placing the ammunition in the loading line of the gun, telescopic rails constructed to form a track for said car, and journaled respectively on a gun part that partakes of the elevation, and on a part of the mount that partakes of the training, the axes of the journals running parallel with the axis of the gun trunnions, a rope tightening member, said member carrying means 110
15. A loading device for turret or stationary guns, provided with an ammunition car hoist, for placing the ammunition in the loading line of the gun, telescopic rails constructed to form a track for said car, and journaled respectively on a gun part that partakes of the elevation, and on a part of the mount that partakes of the training, the axes of the journals running parallel with the axis of the gun trunnions; a rope tightening member, said member carrying means 115
16. A loading device for turret or stationary guns, provided with an ammunition car hoist, for placing the ammunition in the loading line of the gun, telescopic rails constructed to form a track for said car, and journaled respectively on a gun part that partakes of the elevation, and on a part of the mount that partakes of the training, the axes of the journals running parallel with the axis of the gun trunnions, a rope tightening member, said member carrying means 120
17. A loading device for turret or stationary guns, provided with an ammunition car hoist, for placing the ammunition in the loading line of the gun, telescopic rails constructed to form a track for said car, and journaled respectively on a gun part that partakes of the elevation, and on a part of the mount that partakes of the training, the axes of the journals running parallel with the axis of the gun trunnions, a rope tightening member, said member carrying means 125
18. A loading device for turret or stationary guns, provided with an ammunition car hoist, for placing the ammunition in the loading line of the gun, telescopic rails constructed to form a track for said car, and journaled respectively on a gun part that partakes of the elevation, and on a part of the mount that partakes of the training, the axes of the journals running parallel with the axis of the gun trunnions, a rope tightening member, said member carrying means 130

for guiding the hoist rope, normally tending to move in the direction to take up slack in the hoist rope, and maintaining the hoist rope taut while the elevation of the gun is 5 being changed.

15. A loading device for turret or stationary guns, provided with an ammunition car hoist, for placing the ammunition in the loading line of the gun, telescopic rails constructed to form a track for said car, and journaled respectively on a gun part that partakes of the elevation, and on a part of the mount that partakes of the training, the axes of the journals running parallel with 10 the axis of the gun trunnions; a rope tightening member, said member carrying means for guiding the hoist rope, normally tending to move in the direction to take up slack in the hoist rope, and maintaining the hoist 15 rope taut while the elevation of the gun is being changed and having means for resisting sudden movement.

16. A loading device for turret or stationary guns, provided with an ammunition car hoist, for placing the ammunition in the loading line of the gun, telescopic rails constructed to form a track for said car, and journaled respectively on a gun part that partakes of the elevation, and on a part of the mount that partakes of the training, the axes of the journals running parallel with 20 the axis of the gun trunnions; a rope tightening member, said member carrying means for guiding the hoist rope and maintaining 25 the hoist rope taut, while the elevation of the gun is being changed, said member comprising a hydraulic brake having one of its members carried by the gun mount, and the other suspended by the hoist rope.

- 30 17. A loading device for turret or stationary guns, provided with an ammunition car hoist, for placing the ammunition in the loading line of the gun, telescopic rails constructed to form a track for said car, and journaled respectively on a gun part that partakes of the elevation, and on a part of the mount that partakes of the training, the axes of the journals running parallel with 35 the axis of the gun trunnions; and said gun part on which the telescopic rails are journaled, having a rearward extension, forming a chain rammer seat.

- 40 18. A loading device for turret or stationary guns, provided with an ammunition car hoist, for placing the ammunition in the

loading line of the gun, telescopic rails constructed to form a track for said car, and journaled respectively on a gun part that partakes of the elevation, and on a part of the mount that partakes of the training, the 45 axes of the journals running parallel with the axis of the gun trunnions; and said gun part on which the telescopic rails are journaled, having a rearward extension, forming a chain rammer seat, and a chain rammer 50 housing carried on said seat and extending forward over the gun.

19. A loading device for turret or stationary guns, provided with an ammunition car hoist, for placing the ammunition in the loading line of the gun, telescopic rails constructed to form a track for said car, and journaled respectively on a gun part that partakes of the elevation, and on a part of the mount that partakes of the training, the 55 axes of the journals running parallel with the axis of the gun trunnions; and said gun part on which the telescopic rails are journaled, having a rearward extension, forming a chain rammer seat, and a chain rammer 60 housing carried on said seat and extending forward over the gun, and adapted to be swung laterally out of the loading line of the gun when the rammer is not in use.

20. A loading device for turret or stationary guns, provided with an ammunition car hoist, for placing the ammunition in the loading line of the gun, telescopic rails constructed to form a track for said car, and journaled respectively on a gun part that 65 partakes of the elevation, and on a part of the mount that partakes of the training, the axes of the journals running parallel with the axis of the gun trunnions; and said gun part on which the telescopic rails are journaled, having a rearward extension, forming a chain rammer seat, and a chain rammer 70 housing carried on said seat and extending forward over the gun, pivoted to the cradle by its forwardly extending portion, and 75 adapted to be swung laterally out of the loading line of the gun when the rammer is not in use.

The foregoing specification signed at Bar-
men, Germany, this 29th day of May, 1911. 105

MAX BARTHOLDY. [L. S.]

In presence of—

ALBERT F. NUFER,

ALFRED HENKEL.
